WILLIAM ALFERINK

BY *John A. Bonnhardt*
ATTORNEY

UNITED STATES PATENT OFFICE.

WILLIAM ALFERINK, OF CLEVELAND, OHIO, ASSIGNOR OF ONE-THIRD TO WILBERT FRENCH, OF AUSTINBURG, OHIO, AND ONE-THIRD TO JOSEPH WEAVER, OF CLEVELAND, OHIO.

CONVEYER FOR ANNEALING FURNACES.

Application filed September 9, 1927. Serial No. 218,489.

This invention relates to conveyers for annealing furnaces and more particularly to a feeding device and a metal sheet separating device by means of which the so-called good and bad metal sheets are separated and piled up in their respective piles.

The purpose of the invention is to provide a simple means for feeding the metal sheets thru the annealing furnace and separating them as they emerge from the furnace, thereby saving a great deal of labor.

The invention is illustrated in the accompanying drawing in which Figure 1 is a fragmentary view partly in section of the rear part of the furnace and the plate feeding rolls; Fig. 2 is a perspective view of a portion of the front of the furnace with the sheet separating tables and the high and low speed rolls. Fig. 3 is a diagram showing the method of placing the good plates (sheets) on the bad ones.

Referring to Fig. 1, 1 represents the outer wall of the furnace, 2 is a structural steel frame imbedded in said wall and extending through the furnace, both front and rear carrying the various rollers and their brackets. 3 are steel conveyer rollers carried by frame 2 and run the length of the furnace. 4 are the feed rollers supported by bracket 5 attached to frame 2. 6, 7 and 8 are sloping planes that act as guides for feeding the plates into the furnace. 9 represents a good plate and 10 represents a bad plate being fed into the furnace and it will be noted that the bad plate is half way through the roll before the good plate is fed in. This results in an arrangement of plates as shown in diagram of Fig. 3.

By way of explanation it may be well to state that in running a plate or sheet thru the annealing furnace it is customary to use a bad plate on which the plate to be annealed rests, the bad plate providing a sort of protection to the good plate while it passes thru the furnace.

Referring now to Fig. 2, the plates emerging from the furnace are caught by the slow speed set of rollers 11 and from them are fed into a second set of rollers 12, which rotate at a considerably greater speed. The difference of the speed of the two sets of rollers causes the plate in the fast set of rollers to travel faster than the plate in the low speed set, thus separating them and causing a single plate to fall at one time on the horizontal table. Ob-

viously the distance between the set of rollers 15 is slightly greater than the length of one plate. As the bad plate emerges from rollers 12 it is fed forward onto table 13, which table consists of a frame 14 and two sets of rollers 15, and hinged at 16 to frame 2. The continued forward motion of the bad plate causes table 13 to tip, sliding the plate off onto its pile at the end of the apparatus and at same time raising table 17 to a horizontal position. By this time the good plate has reached the fast set of rollers and is fed forward onto table 17 where its weight causes the table to tip sideways sliding the good plate off onto its pile at side of apparatus.

Table 17 is hinged to support 18 at point 19 and is connected to the upper table 13 by means of cable 20 through a ball joint at its lower end. Table 13 has attached to its lower side brackets carrying rod 22 on which balancing weight 23 slides. Weight 23 may be fastened at any point by set screw 24.

A small roller 28 carried at the front of table 13, aids in feeding plates onto table 17 when table 13 is tilted.

I claim:

1. A sheet separating apparatus for furnaces comprising a conveyer adapted to convey upper and lower sheets thereon in overlying relation, and means at the outlet end of the conveyer to separate and discharge the upper and lower sheets respectively to different places said means comprising a pair of receiving devices movable to alternately register the same with the end of the conveyer.

2. An apparatus as set forth in claim 1, the said means comprising an upper tilting table to receive the upper sheets and a lower tilting table to receive the lower sheets in alternation.

3. The combination with a conveyer adapted to carry upper and lower sheets in overlapped relation along the same, of an upper tilting table at the discharge end of the conveyer, adapted to receive the lower sheets, and a lower tilting table at said end, operatively connected to the upper table and adapted to receive the upper sheets, said table being movable to alternately register their ends with the discharge end of the conveyer.

4. The combination with a conveyer adapted to convey superposed overlapping plates, of means to separate the upper and lower plates as they are discharged from the con-

- veyer and to deliver them to different places, said means comprising a pair of separating and delivering devices movable to alternately register the same with the discharge end of the conveyer.
5. The combination with a conveyer adapted to convey upper and lower plates in overlapped relation, of means to separate the plates as they are discharged from the conveyer, comprising upper and lower tilting tables operable to alternately register with the end of the conveyer.
- 10
6. The combination stated in claim 5, one table tilting lengthwise as to the conveyer and the other sidewise.
7. The combination with a conveyer, of means at the inlet end thereof to feed sheets thereto in upper and lower lapped relation, comprising separate feed rolls at different heights and guides associated with the respective rolls.
